UNITED STATES PATENT OFFICE.

RICHARD LOGSTÄDT, OF BERLIN-SCHONEBERG, GERMANY, ASSIGNOR TO WESTINGHOUSE ELECTRIC & MANUFACTURING COMPANY, A CORPORATION OF PENNSYLVANIA.

HIGH-SPEED CIRCUIT INTERRUPTER.

Application filed September 8, 1925, Serial No. 54,934, and in Germany November 4, 1924.

My invention relates to protective apparatus for electrical systems and particularly to high-speed circuit interrupters.

One object of my invention is to provide 5 a circuit interrupter that shall be operated by centrifugal forces.

Another object of my invention is to provide 10 a circuit interrupter that shall utilize magnetic forces for balancing centrifugal forces until the desired conditions for operation of the circuit interrupter exist, whereupon the magnetic forces are overcome and the centrifugal forces operate to open the circuit interrupter.

15 Another object of my invention is to provide a circuit interrupter of the centrifugal type in which the centrifugal forces are always active but are restrained by magnetic forces, whereby upon the elimination of the 20 magnetic forces, the centrifugal forces operate to open the circuit interrupter without the loss of time required to overcome the inertia of the armature, springs and the like.

25 A further object of my invention is to provide a circuit interrupter that shall operate in response to centrifugal forces as distinguished from forces dependent upon energy stored in mechanical devices such as springs, or upon electrical forces such as those required 30 to operate a magnet.

With the continued concentration of enormous amounts of electrical energy in electrical systems, the time element in the operation of circuit interrupters and other protective devices has been given greater consideration by the electrical industries. As 35

40 In order to obtain operation of circuit interrupters in such extremely short periods of time, it has heretofore been necessary that the moving parts be of relatively small mass and be operated by relatively large springs or continuously energized electro-magnets. Such speeds of operation as are required cannot be obtained when it is necessary to accelerate a large mass of material or where 45 it is necessary to build up a magnetic field.

50 I propose to secure the foregoing results by providing a circuit interrupter in which the relatively movable contact members are rotated at relatively high speed, but are pre-

vented from separating by the action of an 55 electro-magnet of such form that, upon the occurrence of undesired conditions in the circuit under control, it is de-energized, whereupon the contact members are separated by the centrifugal forces incidental to 60 the rotative motion thereof.

In the accompanying drawing

Figure 1 is a schematic diagram of a circuit interrupter embodying my invention,

Fig. 2 is a sectional view of my improved 65 circuit interrupter along the section line 2—2 of Fig. 1, and

Fig. 3 is an end view in elevation of the circuit interrupter.

My invention comprises in general, a 70 motor 1, the shaft 2 of which rotates a switch 3 that is constituted by a pair of relatively movable contact members 4 and 5 that are pivotally mounted with respect to the shaft 2 at points 6 and 7, and which are retained in engagement with each other by an electromagnet 8 that is also rotated by the shaft 2.

The switch structure 3 is disposed within 80 a housing 9 that also rotates with the shaft 2.

Referring to Fig. 1, the shaft 2 terminates within the housing 9 and the contact members 4 and 5 are disposed about the projected axis of the shaft beyond the end thereof and are supported upon pins 6 and 7 that are 85 connected directly to the housing 9, through armature members 10 and 11 respectively. Accordingly the contact members 4 and 5 in circuit-closing position occupy their relative 90 positions shown in Fig. 3.

Within the housing 8 there is centrally disposed a core member 12, of rectangular cross-section, that engages with faces or pole pieces 13 and 14 on the armature members 10 and 11 respectively. The armature members 10 and 11 are separated from each other at diametrically opposite positions, thereby forming air gaps 15 in order to permit relative angular movements of the armature members about their axes 6 and 7. However, in order to keep the magnetic reluctance of the air gap 15 at a minimum, the surfaces of the armature members 10 and 11 are inclined in order to present large surface areas.

100 The core member 12 is normally energized by a winding 16 that is connected through slip rings 17 and 18 mounted on the shaft 2 to

a battery 19 or other source of electromotive force. The current traversing the winding 16 may be regulated by varying the potential of the source of electromotive force 5 19. In normal operation, the current traversing the winding 16 is held at a constant value.

The relatively movable contact members 4 and 5 are connected by conductors 21 to slip 10 rings 22 and 23 that are also mounted on the shaft 2 and are connected to any external apparatus (not shown). The conductors 21 extend longitudinally of the winding 16 in parallel relation to the shaft 2 to points beyond the core member 12 and winding 16 where they are bent to engage the relatively movable contact members 4 and 5. Accordingly the stationary contact members 4 and 5, the conductors 21, the winding 16, the core 15 members 12 and the housing 9 are all adapted to rotate about the axis of the shaft 2 when the motor 1 is energized.

Normally, the motor 1 rotates the switch 3, with the winding 16 energized with the result that the contact members 4 and 5 are in engagement with each other, since the ampere turns of the winding 16 are sufficient to overcome the ampere turns of the conductors 21, and the centrifugal forces of armature 20 members 10 and 11 with the result that they are held in engagement with the core member 12. However, upon the occurrence of an overload condition in the circuit comprising the conductors 21 and the relative movable 25 contact members 4 and 5, the ampere turns of that circuit become sufficiently large to neutralize the magnetic effect of the winding 16 upon the core member 12, whereupon the magnetic attraction between the core member 12 and the pole faces 13 and 14, becomes less than the centrifugal forces stored in the armature members 10 and 11 with the result 30 that the armature members 10 and 11 fly outwardly, carrying with them the relative 35 movable contact members 4 and 5 and the circuit is broken.

Inasmuch as the armature members 10 and 11 and the relatively movable contact members 4 and 5 are at maximum speed at all 40 times, the separation of the contact members 4 and 5 depends only upon the magnetic relation between the windings 16 and the current traversing the windings 21, since there are no springs, large masses of material or electromagnet to be energized in order 45 to cause the separation of the contact members. It will thus be seen that I have provided a high speed circuit interrupter that is normally rotated at a speed sufficient to 50 cause immediate separation of the contact members which, in turn, are held in their circuit closing position by an electromagnet that is controlled by the condition in the circuit to be interrupted.

55 Inasmuch as the relative movable contact

members of my circuit interrupter at all times tend to separate by reason of their inherent centrifugal forces, it is not necessary to accelerate any mass of metal or springs or to energize any electromagnet in order to operate the circuit interrupter. With this combination of elements, I am able to open a circuit of large capacity in a very small period of time that may be measured in thousandths of a second.

70 While I have described and illustrated but one embodiment of my invention, it will be apparent to those skilled in the art that various changes, modifications, substitutions, additions and omissions may be made in the 75 apparatus described without departing from the spirit and scope of the invention as set forth by the appended claims.

I claim as my invention:

1. In a switch structure, a pair of relatively movable rotatable contact members, means for holding the relatively movable contact members in a predetermined position relative to each other while under the influence of centrifugal forces incidental to 80 their rotary movement and means for directly controlling the last named means in accordance with the current traversing the contact members.

2. In a switch structure, a pair of relatively movable rotatable contact members, means for holding the relatively movable contact members in a predetermined position relative to each other while under the influence of the centrifugal forces incidental to 85 their rotation and an electrical conductor 90 for controlling the last named means.

3. In combination, a pair of relatively movable contact members, means for imparting rotary movement to the contact members, means for retaining the contact members in engagement, and electrical means for magnetically controlling the retaining means.

4. In combination, a pair of relatively 100 movable contact members, means for rotating the contact members whereby centrifugal forces bias them to circuit-opening position, electromagnetic means for retaining the contact members in engagement, and 105 means for controlling the effectiveness of the electromagnetic means.

5. In combination, a pair of relatively 110 movable contact members, means for rotating the contact members such that centrifugal forces bias them to circuit-opening position, electromagnetic holding means therefor, and an auxiliary winding for controlling the effectiveness of the electromagnetic means.

6. In combination, a pair of relatively 115 movable contact members comprising pole pieces, means for rotating the contact members at such speed that centrifugal forces 120 bias them to circuit-opening position, an 125

electromagnet comprising a core member co-operating with the pole pieces, and an energizing winding controlling the operation of the contact members.

- 5 7. In combination, a pair of relatively movable contact members comprising pole pieces, means for rotating the contact members whereby centrifugal forces bias them to circuit-opening position, and an electromagnet comprising a core member co-operating with the pole pieces, an energizing winding and an auxiliary winding for controlling the operation of the contact members.
- 10 8. In combination, a pair of relatively movable contact members comprising pole pieces, means for rotating the contact members whereby centrifugal forces bias them to circuit-opening position, and an electromagnet comprising a core member co-operating with the pole pieces, an energizing winding and an auxiliary winding for neutralizing the effect of the energizing winding, under predetermined conditions whereby centrifugal forces cause the movable contact members to be separated from the core member, and from each other thereby interrupting the circuit.
- 15 9. In combination, a pair of pivoted relatively movable contact members comprising pole pieces, that are rotated at such speed that centrifugal forces bias them to circuit-opening position, and an electromagnet comprising a core member co-operating with the pole pieces, an energizing winding and an auxiliary winding for neutralizing the effect of the energizing winding, under predetermined conditions whereby centrifugal forces cause the movable contact members to be separated from the core member, and from each other thereby interrupting the circuit.
- 20 10. In combination, a pair of relatively movable contact members comprising pole pieces, means for rotating the contact members whereby centrifugal forces bias them to circuit-opening position, and an electromagnet comprising a core member co-operating with the pole pieces, an energizing winding and an auxiliary winding for neutralizing the effect of the energizing winding, under predetermined conditions whereby centrifugal forces cause the movable contact members to be separated from the core member, and from each other thereby interrupting the circuit.

In testimony whereof I affix my signature.

RICHARD LOGSTÄDT.
